FIGURE 1 is a front elevational view in perspective of a multiple student desk unit embodying the features of my new design;

FIGURE 2 is a front elevational view, partially in section and with parts removed, of the multiple student desk unit illustrated in FIGURE 1;

FIGURE 3 is a sectional view taken along line 3-3 of FIGURE 2;

FIGURE 4 is a sectional view taken along line 4-4 of FIGURE 2; and

FIGURE 5 is a top plan view of the multiple student desk unit illustrated in FIGURES 1 and 2.

The multiple student desk unit is substantially hexagonally symmetrical in construction about its vertical axis. The dominant features of the invention are shown in solid lines.

I claim:

The ornamental design for a multiple student desk unit, substantially as shown and described.
